United States Patent

Des. 236,052
Patented July 29, 1975

236,052

TENNIS RACQUET HOLDER OR THE LIKE

Donald C. Trieschmann, 615 Cherry St.,
Winnetka, Ill. 60093

Filed Nov. 21, 1973, Ser. No. 417,877

Term of patent 3½ years

Int. Cl. D6—06

U.S. Cl. D6—114

FIG. 1 is a perspective view of a tennis racquet holder or the like, embodying my new design;

FIG. 2 is a front elevational view thereof;

FIG. 3 is a side elevational view thereof;

FIG. 4 is a rear elevational view thereof;

FIG. 5 is a top plan view thereof; and

FIG. 6 is a bottom plan view thereof.

I claim:

The ornamental design for a tennis racquet holder or the like, substantially as shown.
